2,434,788

FAT-SOLUBLE VITAMIN CONCENTRATES

Loran O. Buxton, Newark, N. J., assignor to
Nopco Chemical Company, Harrison, N. J., a
corporation of New Jersey

No Drawing. Application April 3, 1944,
Serial No. 529,418

2 Claims. (Cl. 167—81)

1

The present invention relates to the production of vitamin concentrates. More particularly, the present invention relates to the fractionation of vitamin-containing marine oils in order to produce a concentrate consisting largely of vitamin esters.

In the fractionation of marine oils containing vitamins to produce concentrates therefrom, a substantial loss has occurred during fractionation. In other words, the percentage of vitamin found in the extract fraction, and that remaining behind in the residue has been very much less than the vitamin contained in the original oil. Although this loss might have been expected in the fractionation of refined marine oils, particularly those refined in such a manner as to destroy most of the natural antioxidants, such a loss would ordinarily not be expected to occur during the fractionation of crude marine oils still containing a large proportion of natural antioxidants.

It has now been discovered, however, that if a small quantity of antioxidant is added to marine oils prior to fractionation, whether or not these marine oils have been previously refined in such a manner as to destroy a large proportion of the natural antioxidants or are the crude, relatively stable oils, a very substantial increase in the yields of vitamin A ester in the concentrate or extract portion and of vitamin content in the residue occurs.

There is further produced in accordance with the present invention, a vitamin ester concentrate which is relatively stable, and this is particularly true if an antioxidant is used which is largely soluble in the solvent used for fractionation. Such an antioxidant is that prepared in accordance with copending applications Serial Nos. 397,547, now Pat. No. 2,345,578, dated Apr. 4, 1944, and 351,909, now Pat. No. 2,345,576 dated Apr. 4, 1944, i. e. antioxidant concentrates produced by solvent extraction of antioxidant-containing vegetable oils or solids. The present process is particularly applicable to fractionation processes for producing vitamin esters, wherein the solvent used for fractionation is very similar to the solvent used for the extraction of antioxidants in accordance with the aforementioned patents.

It is, therefore, one of the objects of the present invention to fractionate a vitamin-containing marine oil with a solvent capable of extracting a large proportion of the vitamin esters from the marine oil in the presence of a suitable antioxidant.

A second object of the present invention is to

produce stabilized vitamin ester concentrates from vitamin-containing marine oils, whether these oils be refined or crude.

A third object of the present invention is to fractionate a vitamin-containing marine oil by means of a suitable solvent capable of extracting vitamin esters therefrom, and particularly vitamin A, so as to produce a vitamin concentrate from the marine oil, said fractionation being performed in the presence of an antioxidant concentrate produced by extraction of antioxidant-containing vegetable materials with a solvent similar to that used in the fractionation.

Other objects and advantages of the present invention will become apparent from the subsequent description and claims.

As before stated, the present process includes the treatment of various types of marine oils and marine oil concentrates to separate and concentrate the ester portion thereof. Among the materials which may be treated in accordance with the present process are fish oils such as cod liver oil, tuna liver oil, shark liver oil, halibut liver oil, and fish oils from sardine, menhaden, herring and the like. These oils may be previously concentrated in accordance with well known methods, or they may be crude oils. By proceeding in accordance with the present process, marine oils may be treated which have previously undergone a treatment with activated carbon, so that these oils are substantially free of fishy taste and odor and also substantially devoid of natural antioxidants. When such a carbon-refined oil is treated, a vitamin ester concentrate is produced which is substantially devoid of fishy taste and odor.

To such a marine oil there is added a relatively small amount, as for example from about 0.5 to 30%, and preferably from about 1% to 5%, of an antioxidant concentrate produced by solvent extraction of antioxidant-containing materials. Such concentrates may be obtained not only by extracting vegetable oils, but oil-bearing solids. The vegetable oil or oil-bearing solids may be any oil-bearing solid or oil containing naturally occurring antioxidants. The oil-bearing solid may contain all the oil, fat, or wax present in said solid in its natural state, or it may have had a substantial proportion of the fatty material or oil removed. Thus, vegetable materials such as soybean meal or cake, wheat bran, wheat germ, corn germ, corn, grain, oats, rye, olives, sesame seed, cottonseed, cocoa bean, palm kernels, copra, rice, rice germ, flax seed, teaseed, hemp seed, perilla seed, alfalfa seed, etc., may be used as a type of

material from which antioxidant concentrates are extracted. In some instances, antioxidant concentrates may be extracted from fish livers themselves or from fish oils. Various vegetable seeds such as tomato seeds, and animal materials such as egg yolks may also serve as the basic materials from which such antioxidant concentrates are prepared. Vegetable oils and fats such as soybean oil, wheat germ oil, cottonseed oil, palm oil, etc., are also suitable.

As pointed out in the aforementioned patents, Nos. 2,345,576 and 2,345,578, these antioxidants are recovered from fatty materials with which they are associated by extraction with a suitable solvent. The solvent employed in accordance with the aforementioned patents is aliphatic in character and a member of well-recognized chemical classes. Further, the number of carbon atoms in the solvent used is an important factor in determining the availability thereof for use in extracting antioxidants.

The following table sets forth the classes of solvents particularly useful in the production of antioxidant concentrates.

Table

1. Aliphatic and alicyclic monohydroxy alcohols containing from 3 to 6 carbon atoms.
2. Esters formed by the reaction of aliphatic and alicyclic alcohols with aliphatic monocarboxylic acids, said esters containing not more than 8 carbon atoms.
3. Aliphatic and alicyclic aldehydes containing not more than 6 carbon atoms.
4. Aliphatic ketones containing not more than 6 carbon atoms.

Solvents falling within the classes above listed are all liquid aliphatic organic compounds having the properties of being substantially miscible with fatty materials at temperatures above room temperature, i. e. 20° to 25° C., and partially immiscible therewith at temperatures substantially below room temperature, and experiments have shown that solvents falling within these classes of compounds are particularly desirable.

Some of the solvents of the character above described are as follows: n-propyl alcohol, isopropyl alcohol, n-butyl alcohol, n-amyl alcohol, isoamyl alcohol, secondary amyl alcohol, furfuryl alcohol, allyl alcohol, diacetone alcohol, beta-hydroxy ethyl acetate, methyl formate, ethyl formate, ethyl acetate, methyl acetate, isopropyl acetate, glycol diformate, glycol diacetate, methyl levulinate, ethyl levulinate, methyl aceto acetate, ethyl aceto acetate, methyl furoate, vinyl acetate, furfuryl propionaldehyde, crotonaldehyde, acetone, methyl ethyl ketone, acetonyl acetone, and propylene chlorhydrin. Mixtures of these solvents belong to that class of aliphatic organic compounds which has the properties of being miscible with fatty oils at temperatures above room temperature and partially immiscible therewith at temperatures substantially below room temperature; furthermore, it will be noted that the majority of these solvents have relatively low freezing points.

Occasionally, it may be found that certain of the solvents hereinabove mentioned may be too miscible with some of the fatty materials which may be treated to effect a separation of antioxidants therefrom; thus, for example, acetone is too miscible with many fatty materials. However, this condition may be easily corrected by diluting the solvent with either a small amount of water or with some liquid aliphatic organic solvent rela-

tively immiscible with fatty materials. In general, it may be said that the effect of diluting any of the above solvents with water will be to render the solvent more immiscible with fatty materials, so that if difficulty is encountered in effecting proper separation of the antioxidant extracts from the fatty material, this difficulty may generally be overcome by the addition of a small amount of water to the solvent.

10. The solvents preferably employed for the production of the antioxidant concentrates are the aliphatic alcohols containing from 3 to 6 carbon atoms. Of these solvents, isopropanol and diacetone alcohol have proved to be the most successful. The presence of the hydroxyl group seems to impart to these solvents, properties which make them particularly useful.
15. In carrying out the extraction of the antioxidants from the oils and oil-bearing solids with which they are associated, the material to be treated is first mixed with the particular solvent to be employed. The relative proportion of material to solvent may vary widely; preferably, the ratio of solvent to material should be greater than one

20. and, in most cases, mixtures containing between about 2% and about 25% oil are most suitable. Where oil is being treated, it is preferable to cause substantially all the oil to dissolve in the solvent; when employing the preferred solvents complete solution is ordinarily effected most readily by heating the mixture to a temperature substantially above room temperature. However, it is not necessary to cause the oil to dissolve completely in the solvent, since highly active antioxidant fractions may be extracted from the oil and oil-bearing solids by agitating the oil or solid with the solvent at a temperature such that only partial solution is effected. The extraction is preferably carried out in an inert gas atmosphere; furthermore, if fat-soluble vitamins are present in the oil being extracted, it is not advisable to heat the mixture to temperatures substantially in excess of 175° C. if recovery of the vitamins is desired.

25. 45. The antioxidant fraction extracted from the oil may be recovered in any suitable manner. When the oil is completely dissolved in the solvent at somewhat elevated temperatures, the recovery of the antioxidant extract is most conveniently accomplished by cooling the solution to a temperature substantially below room temperature, e. g. between about 0° C. and about -70° C., whereby two layers form.
30. 50. The solvent layer obtained from the extraction above described may be filtered and then treated to remove the solvent therefrom, e. g., by vacuum distillation, whereby an extract is recovered containing relatively large amounts of highly active antioxidants. If desired, water

55. 60. may be added to the extract in order to precipitate some of the glycerides contained therein or some of the sterols may be removed; however, these steps are not essential, since the glycerides and sterols do not inhibit the antioxidant properties of the extract. If the extract contains an excessive amount of free fatty acids, these are preferably removed by treatment with alkali in a solvent medium or by other suitable methods.

65. 70. The extract ordinarily possesses the characteristic odor and color of the oil from which it is obtained and is generally slightly more viscous than the original oil.

Although it is preferred to use antioxidant concentrates extracted from various fatty ma-

terials as above set forth and more completely described and claimed in Patents 2,345,576 and 2,345,578, the present process may be carried out by using other types of antioxidant concentrates than those obtained by solvent extraction of antioxidant-containing vegetable oils or solids. However, it is preferred to use antioxidant concentrates which are extracted in accordance with the methods of the aforementioned patents by means of isopropanol from various vegetable oils and oil-bearing solids such as corn oil, soybean oil, etc.

In addition to the aforementioned specific antioxidant concentrates and the conventional antioxidants, ammonia-treated antioxidant concentrates may also be employed in the practice of the present invention. Such concentrates are described in copending application, Serial No. 528,353, filed March 27, 1944.

After the antioxidant has been added to the marine oil, the antioxidant-containing oil is mixed with a suitable quantity of a solvent which is entirely similar to that used for the extraction of the antioxidant, and as summarized and previously set forth in the table. The solvent, however, may be varied in order to produce concentrates of the highest potency. In general this extraction will produce a solvent layer containing most of the vitamin A ester fraction of the vitamin. Where, however, the solvent is diluted with water, the solvent layer may contain a mixture of both vitamin ester and vitamin alcohol. For example, 99% isopropanol, as will be set forth hereinafter in the specific examples, gives a solvent layer consisting largely of vitamin ester, whereas 91% isopropanol will give a solvent layer containing both vitamin ester and vitamin alcohol. Preferably, the mixture of marine oil and solvent together with antioxidant is heated for a substantial period. However, temperatures should not exceed 175° C. or considerable loss of vitamin content will result. In general, the temperature preferably employed is equivalent to the reflux temperature of the particular solvent used and is of the order of 50° C. In some instances, however, mixing the solvent, marine oil, and antioxidant at ordinary room temperature and allowing the same to stand for a substantial period of time, i. e. from 4 to 12 hours, may be sufficient to extract the vitamin ester content of the marine oil and produce a concentrate. Upon standing at room temperature, two layers will form and the solvent layer will contain the large proportion of the ester, and upon vaporization of the solvent in the presence of nitrogen gas and under a vacuum, a vitamin ester concentrate will be produced.

In general, however, in order to obtain a sharp fractionation, it is desirable to cool the mixture of solvent, marine oil, and antioxidant concentrate to temperatures below 0° C. Preferably, such a quantity of solvent is used as substantially exceeds the quantity of marine oil. From 4 to 50 parts of solvent to 1 part of oil has been found suitable.

After the solvent layer has been separated from the residue, the residue may be again treated any number of times with quantities of solvent of the same order to extract a further quantity of ester from the residue. Thereafter, the fractions may be combined prior to removal of the solvent therefrom. Preferably, the process is carried out in the absence of air and in the presence of an inert gas such as nitrogen,

which may be bubbled through the mixture during fractionation. If it is desired, the process may be carried out in a continuous manner, i. e., by continuously passing solvent and marine oil with added antioxidant through a mixing zone and thereafter continuously cooling and separating the solvent fraction from the residue.

The following examples serve to illustrate the process of the present invention, although the invention is not limited to the specific materials or conditions therein set forth.

Example I

15 Fifty grams of carbon-refined shark liver oil containing 56,000 units of vitamin A per gram were mixed with 200 ml. of 99% isopropanol in the presence of an atmosphere of nitrogen gas, and the mixture heated to 50° C. After thorough mixing, the mixture was cooled to -16° C. After 12 hours at the low temperature, the supernatant isopropanol extract was decanted, and the residual oil layer treated three more times with similar volume portions of isopropanol in exactly the same manner. The four combined 20 isopropanol extract fractions, as well as the residual isopropanol insoluble layer, were freed of isopropanol by distillation in the presence of nitrogen under reduced pressure. The combined extracts yielded 19.5 grams of a vitamin concentrate having a specific vitamin A value of 68,500 U. S. P. units of vitamin A per gram. This consisted largely of vitamin A ester. The residue, which consisted of 28.1 grams, had a specific vitamin A value of 37,400 U. S. P. units per gram. The total oil yield was therefore 95.2% of the original oil, and the total A yield was 35 89.6%.

Example II

40 The same carbon-refined shark liver oil of Example I was treated in precisely the same manner, except that 5% of soybean extract antioxidant was added to the carbon-refined shark liver oil. The soybean oil antioxidant concentrate was obtained by extracting 66.5 pounds of 45 soybean oil with 218 lbs. of 91% isopropanol at 55° C. in the presence of nitrogen gas. Thereafter, the solvent oil mixture was stirred at 50° C. for 15 minutes and then cooled rapidly to 23° C. It was withdrawn from the treatment kettle and 50 then placed in the low temperature refrigerator at -25° C. for 2½ days. Thereafter, the supernatant liquid was decanted and the solid portion reextracted with 206 lbs. of 91% isopropanol in a manner similar to the first extraction. The 55 two extracts were combined and the solvent removed under a vacuum and in the presence of nitrogen gas to form the antioxidant concentrate. The results of the treatment of the refined shark liver oil in the presence of the aforementioned antioxidant concentrate were substantially better than those obtained by the procedure of Example I. Thus the combined extracts yielded 14 grams of oil having a specific value of 91,000 U. S. P. units of vitamin A per 60 gram. The residue yielded 33.4 grams of oil having a specific value of 36,600 U. S. P. units of vitamin A per gram. The total oil yield was 95.8% and the total vitamin A yield 100%. The concentrate obtained after volatilization of the solvent 65 from the extract portion was very much more stable than the concentrate of Example I.

Example III

70 Fifty grams of carbon-refined halibut liver oil having a specific vitamin A value of 86,000 units

per gram were stabilized with 5% of soybean oil antioxidant prepared as described in Example II. The oil was then extracted with 3-200 ml. portions of 99% isopropanol at -16° C. in precisely the same manner as described in Examples I and II. The combined extracts yielded 13.7 grams of oil having a specific value of 151,000 U. S. P. units of vitamin A per gram. The residue yielded 35.6 grams of oil having a specific value of 62,200 U. S. P. units of vitamin A per gram. The total oil yield was 98.6% of the original oil, and the total vitamin A yield was 100%.

The same oil treated in precisely the same manner but without the addition of the antioxidant concentrate gave a total A vitamin yield of only 84.2%.

Although, as previously pointed out, it is preferred to use antioxidant concentrates produced by solvent extraction of various types of vegetable materials, other well-known antioxidants may be used. Such antioxidants may include phosphatides in combination with compounds which exert a synergistic action with the phosphatides. Such compounds include cyclic oxy types of compounds, as, for example, quinones, hydroquinones, naphthoquinones, naphthols, naphtho-hydroquinones, chromans, chromens, coumarones and coumarans. These latter compounds are, of course, antioxidants by themselves and may be used in the proportions hereinbefore set forth, either alone or in combination with phosphatides. Typical examples of such compounds are the alpha-beta-gamma tocopherols, the chroman-5-6 quinones and their precursors which are associated with vitamin E.

As will be noted, the present invention is particularly applicable to vitamin-containing marine oils. The vitamins contained in these oils are predominantly vitamin A, and a lesser proportion of vitamin D. It is therefore desired to point out that when in the claims a "vitamin-containing marine oil" is referred to, it is intended to include all the various types of oils of marine origin and the vitamins, i. e. A and D, normally occurring therein.

Having described my invention, what I claim as new and desire to be secured by Letters Patent is:

1. A process for producing a fat-soluble vitamin concentrate from a fat-soluble vitamin-containing marine oil, which comprises mixing in the presence of an antioxidant concentrate obtained by the normally liquid organic solvent extraction of a natural antioxidant-containing fatty material of vegetable origin a fat-soluble

vitamin-containing marine oil with a solvent selected from the group consisting of aliphatic and alicyclic monohydroxy alcohols containing from 3 to 6 carbon atoms, esters formed by the reaction of aliphatic and alicyclic alcohols with aliphatic monocarboxylic acids, said esters containing not more than 8 carbon atoms, aliphatic and alicyclic aldehydes containing not more than 6 carbon atoms and aliphatic ketones containing not more than 6 carbon atoms, to form a substantially homogeneous solution, cooling the mass to form a solvent layer containing a relatively potent concentrate and a residue layer and separating the solvent layer from the residue layer, the antioxidant concentrate serving to inhibit the loss of vitamin potency through oxidation during the process.

2. A process for producing a fat-soluble vitamin concentrate from a fat-soluble vitamin-containing marine oil, which comprises mixing in the presence of an antioxidant concentrate obtained by the normally liquid organic solvent extraction of a natural antioxidant-containing fatty material of vegetable origin a fat-soluble vitamin-containing marine oil with isopropanol to form a substantially homogeneous solution, cooling the mass to form an isopropanol layer containing a relatively potent concentrate and a residual low potency oil layer and separating the isopropanol layer from the residual layer, the antioxidant concentrate serving to inhibit the loss of vitamin potency through oxidation during the process.
